UNITED STATES PATENT OFFICE.

FRITZ WOERNER, OF HAMBURG, GERMANY.

AUTOMATIC FEED APPARATUS.

SPECIFICATION forming part of Letters Patent No. 700,110, dated May 13, 1902.

Original application filed June 28, 1900, Serial No. 21,973. Divided and this application filed July 2, 1901. Serial No. 66,864. (No model.)

To all whom it may concern:

Be it known that I, FRITZ WOERNER, a subject of the German Emperor, and a resident of Hamburg, in the German Empire, have invented certain new and useful Improvements in Automatic Feed Apparatus, forming divisional portion of my pending application, filed June 28, 1900, Serial No. 21,973, and being described in the following specification.

10 The present invention relates to that class of automatic feed apparatus which when used for feeding a steam-boiler, for instance, give access of the steam at a given water-level to a suitable device, which device by means of 15 its expansion operates a valve of the feed-water pipe until requisite water-level has been reached, when the flow of steam to the said expansion device is cut off by the cooling and consequent contraction of the latter 20 in coöperation with a suitable counterweight closes the feed-water pipe.

With this end in view my invention consists of certain novel features of construction and combinations of parts, as will be hereinafter 25 described with reference to the accompanying drawings, in which—

Figure 1 is a lateral elevation, partly in section, of my improved feed apparatus in which the expansion-tubes exert a direct rotary action 30 on a suitable spindle or shaft which in its turn may be used to open or close the cut-off valve of the supply-pipe. Fig. 2 is a central horizontal section through Fig. 1; and Fig. 3 shows an elevation, partly in section, of a 35 modification of the feed apparatus in which the direct rotary action of the spindle or shaft actuating the cut-off valve is effected by the contraction of the said expansion-tubes.

Similar letters refer to similar parts throughout the several views.

The tubes *a a*, Figs. 1 and 2, are connected at top and bottom by suitable unions *b* and *c*, so as to form an oval-shaped tube-frame, the union *b* being provided with a steam-inlet *d* and the union *c* with a steam-outlet *e*. Both 45 unions are connected and held immovably the proper distance apart by means of tie-rods *f* and *g*, which carry between their inner ends a casing or shell *h*. In the walls of this shell 50 is journaled a spindle or shaft *i*, said shaft carrying a disk *k*. The two tubes *a* are fur-

nished in the middle with clips *l* and *m*, respectively. Attached or pivoted to these clips are rods *n* and *o*, respectively, the hook-shaped ends of which, passing through suitable openings in the end walls of the shell *h*, engage notches *p* and *q* in the circumference of the disk *k*. 55

The shaft *i* is connected with the cut-off valve *r* of the supply-pipe *s* or practically 60 forms the stem of the plug *r'* of such cut-off valve or cock.

On the shaft or stem *i* is mounted a weighted double-armed lever *t*, which causes the return movement of the shaft *i* and closing of the 65 cut-off valve when the tube-frame becomes cooled again. In addition to this the lever *t* may be used at the same time to perform different functions—namely, to act by means of a chain *u* on the damper in order to increase or 70 decrease the draft of the air-current which supplies the fire of the boiler or boilers.

When steam is admitted into the tubes *a a*, the heat instantly expands the same, and the latter cause both legs or members *a* of the 75 tube-frame to move outward away from each other at the same time, and thereby draw the rod *n* in the one direction and the rod *o* in the opposite direction. By this combined movement of the parts the rods *n* and *o* act on the 80 disk *k* in such a manner as to cause the latter, and consequently the shaft or stem *i*, with plug *r'*, to rock and to open the cut-off valve *r* of the supply-pipe *s*.

When the steam-supply into the tube-frame 85 is cut off, the tubes *a* cool and contract again, thereby reversing the action above described, allowing the return movement or closing of cut-off valve or cock *r* by the action of the weighted lever *t* and preventing further passage of water into the boiler. 90

By the above-described construction I get double the effect of the expansion and contraction, because both sides of the tube-frame move in opposite directions at the same time. 95 Consequently the tube-frame, or respectively the cut-off valve, opens more quickly under the influence of the heat to a correspondingly greater extent to give free inlet of the medium fed through the supply-pipe and, vice versa, 100 closes more rapidly when becoming cooler.

In the modification illustrated by Fig. 3 the

tube-frame consists of two pairs of tubes a' . Each pair of tubes is connected in the middle by ball-shaped socket-joints $l' m'$, and the outer extremities of the tubes are again fixed 5 in unions b and c . The joints $l' m'$ are provided with bolts v and w , having external threads and passing through the said joints and being adjusted and held in position therein by means of lock-nuts x . The inner ext- 10 remities of the bolts v and w are furnished with flanges y and z , respectively, each of which is provided with a suitable ball-shaped recess or bearing for the reception of the outer ends of rods n' and o' , the inner ends 15 of which engage the notches p and q , respectively, in the circumference of the disk k . The latter, being carried by the shaft i , is in- 20 closed in a suitable casing h' , as this is obvious from the drawings and fully explained with reference to Figs. 1 and 2.

In the modification shown by Fig. 3 the arrangement is, however, thus: that the valve-shaft i is operated not by the expansion of the tube-frame, but by the contraction of the latter. For this purpose the tube-frame is being held in its expanded position by allowing the steam to pass continuously through the tubes a' . When the steam is cut off, the tubes a' cool and contract, thereby causing 25 both sides of the tube-frame to move inward toward each other at the same time, and thereby pushing or moving the rods n' and o' in opposite direction. By this combined 30 inward movement of the rods n' and o' the disk k , and consequently its shaft i , is rocked in order to open or respectively close the cut-off valve of the supply-pipe, as the arrangement may be. When steam is again admitted, the heat instantly expands the tubes a' , 35 and the latter cause both sides of the tube-frame to move outward again, thereby reversing the action above described and allowing or enabling the weighted lever t to rock the shaft i in the opposite direction and 40 to close thereby the cut-off valve of the supply-pipe.

Having fully described my invention, what I claim, and desire to secure by Letters Patent, is—

50 1. An automatic regulating device comprising a pair of steam-legs connected to an inlet-union at one end and to an outlet-union at the opposite end, said legs adapted to diverge or expand, and converge or contract under varying temperatures, a spindle, means operated by the steam-legs when displaced in one direction to rock said spindle in one direction, and means automatically rocking said spindle in a reverse direction on the displacement 55 of the steam-legs in a reverse direction, for the purpose set forth.

2. An automatic regulating device, comprising a pair of steam-legs connected to an inlet-union at one end and to an outlet-union at 60 the opposite end, said legs adapted to diverge or expand and converge or contract under varying temperatures, a spindle, means operated

by the steam-legs when displaced in one direction to rock said spindle in one direction, and a weighted lever secured to said spindle 70 to rock the same in a reverse direction, for the purpose set forth.

3. An automatic regulating device, comprising a pair of steam-legs connected to an inlet-union at one end and to an outlet-union at 75 the opposite end, said legs adapted to diverge or expand and converge or contract under varying temperatures, a spindle, means operated by the steam-legs when displaced in one direction to rock said spindle in one direction, 80 and a two-armed lever having one of its arms weighted, said lever secured to the spindle to rock the same in a reverse direction, for the purpose set forth.

4. In an automatic boiler-feeding device, 85 the combination with the feed-pipe, its valve and valve-stem; of a pair of steam-legs connected at one end to a steam-inlet union and at the opposite end to a steam-outlet union, said steam-legs adapted to diverge or expand 90 and converge or contract under varying temperatures, means operated by the steam-legs when displaced in one direction to rock the aforesaid valve-spindle in one direction and means automatically rocking said spindle in 95 a reverse direction on the displacement of the steam-legs in a reverse direction, for the purpose set forth.

5. In an automatic boiler-feed, the combination with the feed-pipe, its valve and valve-stem and a notched disk secured thereto; of 100 a pair of steam-legs connected to a steam-inlet union at one end and to a steam-outlet union at their opposite end, said legs adapted to diverge or expand and converge or contract 105 under varying temperatures, rods actuated by the displacement of the steam-legs in one direction and engaging the notches in the disk on the valve-spindle to rock the same in one direction, and means automatically rocking 110 said spindle in a reverse direction on the displacement of the steam-legs in a reverse direction, for the purpose set forth.

6. In an automatic boiler-feed, a pair of 115 steam-legs each composed of two tubes and an intermediate hollow union, said legs connected at one end to a steam-inlet union and at the opposite end to a steam-outlet union and a bolt extending through each of the aforesaid intermediate unions, said bolts provided 120 with recessed heads at their proximate ends; of a boiler-feed pipe, its valve and valve-stem, a weighted lever, and a disk secured to said stem, said disk having oppositely-arranged notches p and q and oppositely-arranged rods seated in the recesses in the heads of the aforesaid bolts, the free beveled ends 125 of said rods projecting into the notches p , q , respectively, substantially as and for the purpose set forth.

FRITZ WOERNER.
